UNITED STATES PATENT OFFICE.

THEODORE F. HUSSA, OF MONTCLAIR, NEW JERSEY.

ELEMENT FOR SINGEING APPARATUS.

1,321,828.

Specification of Letters Patent. Patented Nov. 18, 1919.

Application filed January 15, 1918. Serial No. 211,915.

To all whom it may concern:

Be it known that I, THEODORE F. HUSSA, a citizen of the United States, residing at Montclair, in the county of Essex and State 5 of New Jersey, have invented certain new and useful Improvements in Elements for Singeing Apparatus, of which the following is a specification, reference being had therein to the accompanying drawings, 10 which form a part thereof.

In singeing apparatus used in the textile art, it is a common practice to pass individual threads or fabric, in close juxtaposition to a flaming element to remove the fluff 15 therefrom. In some types of such apparatus, the element consists of suitable gas burners, while in other types, platinum elements brought to an incandescent state by being included in an electrical circuit, are 20 employed. With the use of elements of the latter type, it is customary to cause a current of air to pass about the element to remove the fluff or prevent its accumulating upon the element itself.

Platinum elements are not only expensive 25 to produce by reason of the quantity of the metal necessarily incorporated in the element, but the renewal of these elements as the result of deterioration from continued 30 use makes the upkeep of the apparatus expensive.

In view of these conditions there has been a persistent effort to produce elements of metal other than platinum which may be 35 brought to the desired state of incandescence to properly singe the threads or fabric, with an economy in current consumption which will make their use as a substitute for platinum elements feasible.

The object of my invention is the production of an element which will not readily 40 oxidize when brought to an incandescent state, even when subjected to the direct action of a current of air; and which may be less expensively produced than the ordinary 45 platinum element. A further object of the invention is to produce an element which will not rapidly deteriorate as the result of frequent expansion and contraction thereof, 50 or throw off small incandescent particles which might tend to injure the thread or fabric being treated.

The invention consists primarily in an 55 element for singeing apparatus consisting of an alloy of nickel and chromium adapted to be readily brought to an incandescent

state; and in such other novel characteristics as are hereinafter set forth and described and more particularly pointed out in the claims hereto appended.

60

Referring to the drawings:

Figure 1 is a side view, partly in section, of an element for use in singeing threads; and

Fig. 2 is a perspective view of an element 65 for use in singeing fabrics.

Like letters refer to like parts in both views.

In the embodiment of my invention shown in Fig. 1 of the drawings, *a* indicates a 70 troughed section adjacent which the thread is passed in removing fluff therefrom. This element is provided at one end thereof with an extension *b* adapted to be connected with one electrical terminal, which extension 75 projects at substantially right angles to the trough *a* and is substantially straight. At the other end of said trough is an extension *c* having an end *d* extending substantially parallel with the trough *a*; the extension 80 *c* extending at substantially right angles to said trough. By this construction the extensions *b* and *c* provide sufficient flexibility in the element structure to permit the free expansion and contraction of the trough *a* 85 and avoid the bulging of the trough while in use.

In the form of the invention shown in Fig. 2, the construction is as heretofore described, with the exception that instead of employing 90 a trough *a*, I employ an arched plate *e*, this form of the invention being adapted for use in singeing fabric.

In both forms of the invention, the portion of the elements adjacent which the 95 thread or fabric passes, and also preferably the extensions for connecting this portion with the electrical current, is made of an alloy of nickel and chromium which I have found in practice to be highly satisfactory 100 in an element of this character.

This alloy, I have found, becomes incandescent with a voltage sufficiently low to 105 permit the use in the apparatus of a number of elements connected in series in an ordinary lighting circuit. There is no tendency toward oxidation, and the repeated expansion and contraction thereof does not result in molecular disturbances resulting in heat checking, or the discharge of small 110 particles of the metal when it is brought to incandescence.

I have found that the addition of other metals to the alloy, such as iron, makes the alloy unsuitable for use as an element for singeing apparatus, it being necessary to use only commercially pure nickel and commercially pure chromium in order to provide an element which may be used for the purpose intended. The thickness of the extensions *b* and *c* of the element is such as to offer little or no resistance to the expansion of the trough portion *a*, or the arched portion *c*.

While the voltage required to bring an element made in accordance with my invention to incandescence is somewhat higher than with a platinum element, the amperage is lower. The current consumption, however, is somewhat higher with an element made in accordance with my invention than with a platinum element, but the difference does not exceed 20% and the additional expense of operation is not sufficiently great to overcome other advantages, such as the original cost of installation and the reduced cost of upkeep as compared with a platinum element.

I am aware that an alloy consisting of chromium and nickel alone, or with other metals, is well known in the metallurgical art, but I believe that I am the first to discover that the use of an alloy consisting only of chromium and nickel in an element for a singeing apparatus, imparts to said apparatus characteristics highly desirable in securing an effective singeing of threads or fabric.

It is not my intention to limit the invention to the particular structural characteristics shown in the accompanying drawings,

it being apparent that such may be varied 40 without departing from the spirit and scope of the invention.

Having described the invention what I claim as new and desire to have protected by Letters Patent is:—

1. An element for singeing apparatus consisting of an alloy of nickel and chromium adapted to be readily brought to an incandescent state.

2. An element for singeing apparatus 50 consisting of a portion adapted to act upon the material to be singed, integral extensions at the opposite sides thereof projecting at substantially right angles thereto, one of said extensions having an inturned 55 portion extending substantially parallel with the portion operative upon the material, said element being formed of an alloy of nickel and chromium adapted to be readily brought to an incandescent state. 60

3. An element for singeing apparatus consisting of a trough section having integral extensions at opposite ends thereof projecting at substantially right angles thereto, one of said extensions being inturned and 65 projecting substantially parallel with said trough, said trough and said extension being formed of an alloy of nickel and chromium adapted to be readily brought to an incandescent state. 70

In witness whereof, I hereunto affix my signature, in the presence of two subscribing witnesses, this 19th day of December, 1917.

THEODORE F. HUSSA.
